DESIGN FOR A CAKE ORNAMENT

Leon D. Bush, Chicago, Ill.

Application July 11, 1947, Serial No. 140,225

Term of patent 14 years

(Cl. D29—1)

To all whom it may concern:

Be it known that I, Leon D. Bush, a citizen of the United States of America, residing at Chicago, in the county of Cook and State of Illinois, have invented a new, original, and ornamental Design for a Cake Ornament, of which the following is a specification, reference being had to the accompanying drawing, forming a part thereof, wherein:

Fig. 1 is a front elevation of a cake ornament showing my new design;

Fig. 2, a side elevation; and

Fig. 3 a rear elevation.

I claim:

The ornamental design for a cake ornament, substantially as shown.

LEON D. BUSH.
